APPARATUS FOR BLOWING OIL WELLS

John B. Hawley, Jr., Minneapolis, Minn.

Application April 10, 1944, Serial No. 530,312

17 Claims. (Cl. 103—234)

This invention relates to an apparatus for blowing oil from an oil well or from an oil well casing. The methods heretofore used in blowing oil from oil wells have been quite inefficient due to the fact that a very large volume of compressed air has been wasted. It is expensive to compress the air and it is desirable to use as little of compressed air as possible.

It is an object of this invention therefore, to provide an apparatus for blowing oil from an oil well or oil well casing which requires the use of a comparatively small quantity of compressed air.

It is another object of the invention to provide an apparatus for blowing oil from an oil well or oil well casing in which a casing extending down to the oil supply is closed adjacent its bottom to form a chamber above said oil supply, a volume of air is supplied to said chamber to form a pressure therein and this pressure if sufficient, is used to actuate a supply of air under pressure through an air supply conduit extending to said chamber to force oil through a discharge conduit extending to the oil supply. It is also an object of this invention to provide an apparatus for blowing oil from an oil well which comprises a casing extending down to the oil supply, means for closing off said casing adjacent the oil supply to form a chamber above said supply, a comparatively large discharge conduit extending downwardly through said casing to said oil supply, an oil supply conduit extending downwardly in said casing to said chamber, means for supplying a volume of air through said air supply conduit to said chamber to form a pressure therein which pressure can be utilized to connect a source of air under pressure to said air supply conduit to force oil through said discharge conduit.

It is a further object of the invention to provide such an apparatus as set forth in the preceding paragraph, together with means operated by the column of discharged oil in said discharge conduit for shutting off the supply of air under pressure to said air supply conduit.

It is still another object of the invention to provide an apparatus for discharging oil from an oil well comprising a casing extending down to the oil supply, a packer in said casing adjacent the lower end thereof whereby a chamber is formed above said oil supply below said packer, a discharge conduit extending through said packer to the oil supply, a small conduit extending through said packer to said chamber together with means for supplying a volume of air through said small conduit to said chamber for forming a pressure therein and means for utilizing said

pressure to force air under pressure through said small conduit to discharge air through said discharge conduit.

It is another object of the invention to provide an apparatus for blowing oil from an oil well comprising a casing extending to the oil supply, means for closing off said casing adjacent the bottom thereof to form a chamber above said oil supply, a discharge conduit extending through said means to adjacent the bottom of said casing and into the oil supply, a small conduit extending through said means into said chamber, means for supplying a volume of air through said small conduit to said chamber, a pressure means controlling a supply of air under pressure, which supply is adapted to be connected to said small conduit and a means actuated by the pressure in said chamber for controlling said pressure means whereby the pressure in said chamber if sufficient, will cause said pressure means to connect said source of air under pressure to said small conduit for forcing oil through said discharge conduit.

It is still further an object of the invention to provide an apparatus such as set forth in the preceding paragraph together with means adjacent the top of said discharge conduit actuated by the discharged body of oil for acting on said pressure means to cut off the supply of air under pressure to said small conduit.

It is more specifically an object of the invention to provide an apparatus for blowing oil from an oil well comprising a casing extending downwardly to the oil supply, a packer adjacent the bottom of said casing forming a chamber above said oil supply, a discharge conduit extending through said packer down into the oil supply, a small conduit extending through said packer to said chamber, a source of air under pressure, a pressure means such as a diaphragm valve for shutting off said source of air under pressure from said small conduit, means for exhausting the pressure in said chamber, means for supplying a volume of air to said chamber to form a pressure therein, a pilot valve actuated by said pressure if sufficient and connections between said pilot valve and said pressure means whereby the latter is actuated to supply air under pressure to said small conduit and force oil through said discharge conduit.

These and other objects and advantages of the invention will be fully set forth in the following description made in connection with the accompanying drawings in which like reference char-

acters refer to similar parts throughout the several views and in which—

Fig. 1 is a somewhat diagrammatic view of the apparatus used in carrying out the above described method;

Fig. 2 is a similar view showing some parts of the apparatus in different positions; and

Fig. 3 is a view similar to Fig. 1 showing a modified form of the invention, some parts being omitted.

Referring to the drawings a portion 10 of the stratum containing the oil supply is shown and a casing 11 extends from the ground level 12 to the stratum 10. A body of cement or similar material 13 is disposed about the bottom of casing 11 at the bottom thereof forming a seal and also assisting to steady or hold said casing in position. In accordance with the present invention a packer 14 is provided and disposed adjacent the bottom of casing 11 so that a chamber 15 is formed above the level 16 of the oil supply as shown in Fig. 1. The level of oil changes at different times. A discharge conduit 18 of comparatively large size is provided, the same extending through packer 14 downwardly in casing 11 to a point a considerable distance below the oil supply. While this casing could be variously disposed in the embodiment of the invention illustrated it is shown as having a sleeve 19 secured thereto which is attached to a framework 20 extending across the top of casing 11 and supported on the ground. The packer 14 comprises a body of expansible or resilient material 14a at the intermediate portion thereof below which is a rigid member such as a casting 14b. Member 14b is shown as supported on a collar or flange 18a formed on or secured to conduit 18. Another member or casting 14c rests on the top of portion 14a, it being noted that the diameter of members 14b and 14c is somewhat less than the inner diameter of casing 11. Conduit 18 extends freely through portions 14a and 14c but as stated, supports portion 14b and substantially fits therein. A plate 14e surmounts member 14c and has an upwardly extending hub 14f in which is secured the lower end of a small pipe or conduit 22 which extends below member 14b into chamber 15 and extends upwardly above casing 11. Conduit 22 passes loosely through plate 14e. With the described structure it will be seen that member 14a will be compressed between member 14b and members 14c and 14e. The weight of conduit 22 presses on the top of member 14a so that said member is compressed and expanded against the inner wall of casing 11 to tightly seal the same. Since the casing 11 may be approximately 3000 feet in length the weight of conduit 22 is considerable.

Conduit 22 extends above casing 11 and is connected to a valve casing 23 having a valve seat above the top of conduit 22 with which cooperates a valve 24 having a valve stem 24a extending through the top of casing 23 and through a casing 25 having extending transversely thereof a flexible diaphragm 26. Valve rod 24a has a flange at its top pressing against or secured to the bottom of diaphragm 26. A compression coiled spring 27 overlies the center of diaphragm 26 and engages the top of casing 25. Casing 25 has an exhaust opening or vent 25a above diaphragm 26. A small conduit 29 extends from casing 25 below diaphragm 26 and extends to a valve casing 30 having a valve seat 30a with which cooperates a valve 31 to close the opening or passage to a conduit 32 opening to the atmosphere. Valve 31 has a valve stem 31a

which extends to one side of a casing 33 having a diaphragm 34 extending transversely thereof substantially at the center thereof. Valve stem 31a will be secured to one side of said diaphragm 34 and a compression coiled spring 35 presses at one end upon diaphragm 34 and at its other end against one side of casing 33, said spring acting to hold valve 31 in closed position. A conduit 36 extends from the other side of casing 33 into discharge conduit 18 and has a downturned end 36a which may be in the form of a Pitot tube adapted to be acted upon by a column of oil moving in discharge conduit 18. Discharge conduit 18 is shown as extending laterally and having a terminal discharging into a storage tank 38 illustrated as supported upon a framework 39 and having a valve controlled discharge means 40. Casing 33 has a vent opening 33a at the side of diaphragm 34 at which spring 35 is disposed.

Conduit 42 connects with conduit 29 and extends to and is connected to the chamber in a pilot valve casing 43. Casing 43 has a vent opening 43a adjacent its upper end and a plug 44 threaded in its top, the same having an angular or hexagonal portion 44a to which a tool may be applied for turning said plug. The lower end of plug 44 is reduced in diameter and disposed within a compression coiled spring 45, the other end of which surrounds a projection upstanding from a plunger valve 46. Valve 46 has spaced portions 46a and 46b fitting in the bore of casing 43, which portions are connected by a portion 46c of reduced diameter. Another valve 47 fits in the bottom of the bore of casing 43, the same having a short projecting portion 47a of reduced diameter at its lower end and a longer portion 47b of reduced diameter at its upper end, which latter is shown as engaging the bottom of portion 46b. A branch conduit 49 extends from conduit 42 and communicates with the bore of casing 43 between portion 46b and valve 47 in the position shown in Fig. 1. Casing 43 has a vent or exhaust opening or conduit 50 extending therefrom between portions 46a and 46b in the position shown in Fig. 1. Another conduit 51 communicates with the bore of casing 43 intermediate the ends of valve portion 46a in the position shown in Fig. 1 and said conduit 51 is provided with a throttle valve 52. Conduit 51 extends to and is connected to a conduit 54 which connects with a conduit 55. Conduit 55 is connected to the chamber in valve casing 23 above valve 24. Conduit 55 also extends to a large tank or accumulator 56 which may be connected by conduit 57 to an air compressor.

The lower portion of the bore of pilot valve casing 43 has connected thereto a conduit 59. Conduit 59 extends to the casing of a rotary cycle control valve 60 having a shaft 61 secured thereto which is driven by any suitable mechanism such as a worm wheel gear 62 in turn driven by a worm gear 63 secured to a shaft 64 which is driven from a motor 65 preferably through change gears indicated diagrammatically as 66. Rotary valve 60 has a passage 60a extending diametrically therethrough and which is adapted to connect a passage 60b with a passage 60c, which latter is in turn connected to conduit 59. Passage 60b is connected to conduit 68 which is connected to conduit 22 below valve casing 23. The passage 60a is also adapted to connect a passage 60d extending to the atmosphere with a passage 60e also connected to conduit 68. The passage 60d has quite a long port 60f extending about the periphery of rotary valve 60, which port ex-

tends close to passage 60c so that in the rotation of valve 60 port 60f may be connected momentarily to the passage 60c by the passage 60a. A conduit 70 extends from passages 60b and 60e to the casing 71 of a plunger valve 72 having spaced plungers 72a and 72b connected by a reduced portion or rod, plunger 72b having a projection 72c extending into a compression coiled spring 74, one end of which engages the bottom of plunger 72b and the other end of which engages the bottom of casing 71. Casing 71 is provided adjacent its top and bottom respectively with vent openings 71a and 71b. Plunger 71 has a pin or small rod projecting from its upper end through the top of casing 71 and disposed to be acted upon by a rotary cam 75 secured to shaft 81. A conduit 76 communicates with the bore of casing 71 between plungers 72a and 72b in the position shown in Fig. 1, which conduit 76 is connected to a tank or container 77 for compressed air. Another conduit 78 extends from the bore of casing 71 intermediate the ends of plungers 72b as shown in Fig. 1, which conduit 78 is connected to conduit 54.

As stated, the invention has to do with the automatic operation or cycling that will apply air to the oil in the oil supply or reservoir at the bottom of casing 11 at a pressure that is a fraction of the pressure required to discharge a full column of oil in discharge conduit 18. For instance, in a well in which it would be approximately 3000 feet in casing 11 to the oil supply approximately 1200 pounds of pressure would be required to discharge 19 barrels or more of oil in a blowing cycle since 19 barrels would fill the conduit 18, assuming the same to be a 2½ inch tubing. If the blowing were properly timed so that when 800 feet of the tubing would be filled equivalent to only five barrels, then 300 pounds of pressure would discharge a slug of oil approximately 800 feet long in discharge conduit 18. While various sizes might be used for conduit 22, this will preferably be made of one inch tubing. The time of discharging the oil is set by a time cycling valve, which in the embodiment of the invention illustrated, is valve 60, and this will be operated in accordance with the flow of oil in the casing 11.

When the reservoir or oil supply in the bottom of casing 11 has reached practically up to member 14b as shown in Fig. 1, valve 60 which will be constantly rotated at the desired speed will come into position to connect passage 60e with passage 60d. This, through conduit 22 and 68, will connect chamber 15 to the atmosphere. This will exhaust any pressure which may have developed above the supply of oil. Oils in the ground contain gases such as propane, butane, methane and others and some pressure may develop in chamber 15. In the rotation of cam 75 valve 72 will be intermittently depressed against the pressure of spring 74 and when the chamber between plungers 72a and 72b moves downwardly conduit 70 is shut off and conduits 76 and 78 are connected for a period. A charge of air under pressure from accumulator 56 will then pass through conduit 54 and conduit 78 through the chamber in casing 71 and conduit 76 to tank or container 77. This tank will then be charged with a supply of air under pressure. This charge is retained in the tank as valve 72 is quickly moved upward by spring 74 as cam 75 rotates shutting off conduit 78. In the further rotation of valve 60 it comes to the position shown in Fig. 1 and passage 60b is closed. When valve 72 is moved

upward by spring 74 the charge of air in tank 77 can then discharge through conduit 76, the chamber in valve casing 71 between plungers 72a and 72b as shown in Fig. 1, through conduit 70, conduit 68 and conduit 22. A volume of air is thus charged into or supplied to chamber 15. Chamber 15 has just previously been exhausted of pressure so that the pressure therein when air is supplied from tank 77, will be that caused by said charge of air. If the level of oil has risen so as to be close to the packer 14 as shown in Fig. 1, this pressure will be rather high. If the level of oil is lower, the pressure will be comparatively small. In the continued rotation of valve 60 passage 60a will come into alignment with passages 60b and 60c and a communication will then be established through conduit 22, conduit 68, passage 60b, passage 60c and conduit 59 to the lower part of valve casing 43. If the pressure in chamber 15 exceeds a certain amount, plunger 47 will be lifted, thus lifting valve 46. The vent passage 50 will be closed by plunger 46b and the conduit 51 will be uncovered by plunger 48a. Air under pressure can then pass from accumulator 56, conduit 55, conduit 54, conduit 51 through throttle valve 52 to the bore of valve casing 43 between plungers 46a and 46b and through conduit 42 to the lower chamber in casing 25. This pressure will lift the central part of diaphragm 26 against the pressure of spring 27 and this will lift valve rod 24a and valve 24. Air under full pressure in accumulator 56 can now pass through conduit 55 through valve casing 23 and downwardly around valve 24 into conduit 22. This air under the desired pressure is thus delivered to chamber 15. This pressure will force out the accumulated oil in the bottom of casing 11 until said oil level drops below the lower end of conduit 18. The body or slug of oil will then be forced upward in discharge conduit 18 by the air and will be discharged into the tank 38. When the body or slug of oil approaches the top of conduit 18 it will engage and act on the tube 36a which has an open lower end. A pressure will be set up in conduit 36 and this will act to move diaphragm 34 in casing 33 to the left as shown in Fig. 1. This will compress spring 35 and open valve 31. When valve 31 is open the pressure at the lower side of diaphragm 26 in casing 25 is exhausted through conduit 29, valve casing 30 and conduit 32. Valve 24 can then move to its closed position by gravity and the action of spring 27. The body or slug of oil moving upward in discharge conduit 18 has attained such velocity when it reaches tube 36a that it will continue on upward and be discharged into tank 38. When conduit 29 was connected to the atmosphere as described, through casing 30 and vent pipe 32 the pressure below valve 46 was also exhausted through conduit 49. It will also be noted that immediately after passage 60c is cut off by the rotation of valve 60 and after pressure has been supplied to the bottom of plunger 47 which may be called a shuttle valve that the pressure below valve 47 will be exhausted by passage 60a spanning the port 60f and opening 60c. This will allow valve 47 to drop to the position shown in Fig. 1 so that when the pressure is exhausted from beneath valve 46 through conduit 49 valve 46 can drop to its normal position as shown in Fig. 1. Valve 46 is also moved downwardly by spring 45. The tension of spring 45 can be varied by turning plug 44 to regulate the pressure on pilot valve 46 to suit different conditions in different wells.

In Fig. 3 a modified form of the invention is shown in which casing 11 is used and the concrete or cement 13 is shown around the bottom thereof. A packer 85 is disposed adjacent the bottom of casing 11 and some distance above the oil supply. This packer has a lower member or casting 85a supported upon an air supply pipe 86, which pipe 86 extends to the bottom of the well and is supported on said bottom. Pipe 86 fits into a bore in member 85a and against a shoulder therein so that as stated, member 85a rests upon pipe 86. Packer 85 also includes a body of compressible or resilient material 85b and another top member 85c is disposed above and rests upon the material 85b. Member 85c has a conduit or cylindrical portion 85d extending downwardly therefrom and fitting in portion 85b, the same having a peripheral flange or collar 85e at its lower end which fits in a bore in member 85a. An upper air supply pipe 87 has its lower end fitting in a bore in member 85c and this pipe 87 extends upwardly to a connecting member 90, pipe 87 being threaded into member 90. Member 90 has a central bore 90a which flares upwardly to an enlarged portion 90b. The pipe 91 extends into and is secured to member 90, the same communicating with bore 90a and being adapted to form an air supply so that air can be supplied to air pipes 86 and 87. Packing or closure members 92 are disposed in bores 90a and 90b and are held in place by a follower 93 having a portion fitting in bore portion 90b and held in position by headed and nutted bolts 94 extending through its outer portion and into the top of member 90. An oil discharge pipe 96 extends centrally downwardly in casing 11 and inside of air supply pipes 86 and 87, and thus through packer 85. Pipe 96 will be supported in a tapered block or plug 98 through which it extends, said plug being fitted into a tapered bore in the top member 99a of a frame 99 resting upon the ground. The ground level as before described, is shown as 12. Air supply pipe 86 is provided with a plurality of holes or openings 86a a short distance below packer 85, and while these might be variously arranged, in the embodiment of the invention illustrated, they are shown as disposed in vertically spaced rows. Said conduit 86 also has a plurality of similar holes 86b some distance below the holes 86a and a short distance above the lower end of oil discharge pipe 96. Oil discharge pipe 96 will, of course, extend a predetermined distance into the oil supply.

In operation air supply pipes 87 and 86 will take the place of air supply pipe 22 shown in Figs. 1 and 2, and will be connected to the valve casing 23 and to the valve 60 as shown in said figures. When the pipe 87 is connected to the air supply from accumulator 56, as above described, this air will force the oil which has risen to a level adjacent packer 85 downwardly and up through oil discharge pipe 96. The oil will be discharged until the level drops below the lower holes 86b. After the oil drops below holes 86a, air will pass through said holes to exert pressure on the oil in casing 11 and force it through holes 86b and into pipe 96. The oil will be forced out until it drops below the lower end of pipe 96. The oil originally enters pipe 86 through holes 86b and 86a. A body or slug of oil will thus be discharged through pipe 96 as above described. Pipe 96 will be provided with the tube 36a and connections as shown in Figs. 1 and 2. The control of air to pipe 87 and the preliminary exhausting of the pressure above the oil supply and

just below packer 85 in the cycle of operations will be performed as described in connection with Figs. 1 and 2. The construction shown in Fig. 3 permits the use of a bottom support type of packer where the weight of the upper and larger diameter air supply conduit 87 is used to expand the compressible member 85b of the packer.

From the above description it will be seen that I have provided a very efficient apparatus for blowing oil wells. It will be noted that a comparatively small volume of compressed air is used to discharge the slug of oil. This is merely the volume that passes from the accumulator down through conduit 22 and upward beneath the body or slug of oil until it reaches and operates valve 31. It will be understood that the discharge tube 18 will extend below packer 14 a distance determined by the size of the slug of oil to be discharged. If it were desired to discharge five barrels of oil in each body or slug of oil discharged this distance could be 100 feet with a 2½ inch discharge conduit and a 7 inch casing. The timing of valve 60 of course determines the periods of blowing. There must be sufficient oil on hand to be blown out and to create a pressure sufficient to operate pilot valve 46.

There are some wells which naturally and automatically blow when the pressure above the oil level becomes sufficient. The periods of blowing of such wells could be controlled by a method and apparatus such as above described. The volume or amount of air delivered to chamber 15 by valve 60 can be determined by varying the size of the tank 11. It will be obvious that the method and apparatus will have a high degree of utility for the purpose intended.

In some wells where the natural rate of oil accumulation in the pocket tapped is fixed and known, the need for repeatedly admitting test charges of air to ascertain whether or not the fluid level has risen to the desired blow point, as described in the foregoing, would not occur and the rotary control valve 60 would be replaced by a simple mechanical or electrical timing circuit to open and cut off air flow in accordance with the cyclic demands of the particular well.

It will of course be understood that various changes may be made in the form, details, and proportions of the apparatus without departing from the scope of applicant's invention, which generally stated, consists in an apparatus capable of carrying out the objects above set forth and as defined in the appended claims.

What is claimed is:

1. An apparatus for blowing an oil well having in combination, a casing extending to the oil supply, a packer disposed in said casing adjacent said oil supply for sealing said casing and forming a chamber below said packer, an air supply conduit in said casing extending through said packer, a source of air under pressure, an oil discharge conduit in said casing extending through said packer to below the surface of said oil supply, means for creating a pressure in said chamber and means controlled by said pressure for connecting said source of air to said air supply conduit for forcing a body of oil through said discharge conduit.

2. The structure set forth in claim 1 and means actuated by said discharged body of oil for disconnecting said source of air under pressure from said air supply conduit.

3. An apparatus for blowing an oil well having in combination, a casing extending to the oil supply, a packer disposed in said casing adjacent

said oil supply for sealing said casing and forming a chamber below said packer, an air supply conduit in said casing extending through said packer, a source of air under pressure, an oil discharge conduit in said casing extending through said packer to below the surface of said oil supply and periodically acting means for successively exhausting pressure from said chamber, supplying a volume of air to said chamber and connecting said chamber to said source of air under pressure.

4. The structure set forth in claim 3 and a pressure means to which said chamber is connected after said volume of air has been supplied thereto acting to connect said source of air under pressure to said chamber.

5. An apparatus for blowing an oil well having in combination, a casing extending to the oil supply, a packer disposed in said casing adjacent said oil supply, an air supply conduit in said casing extending through said packer, a source of air under pressure, an oil discharge conduit in said casing extending through said packer to below the surface of said oil supply, means for discharging a volume of air through said air supply conduit above said oil supply to form a pressure thereabove and means for supplying air under pressure through said air supply conduit should said pressure exceed a certain amount.

6. The structure set forth in claim 5, said first mentioned means including an air reservoir and means for periodically charging it with air under pressure.

7. An apparatus for blowing an oil well having in combination, a casing extending to the oil supply, a packer disposed in said casing adjacent the oil supply, a comparatively small conduit in said casing extending through said packer, a source of air under pressure, an oil discharge conduit in said casing extending through said packer to below the surface of the oil supply, means for discharging a volume of air through said first mentioned conduit to form a pressure above said oil supply and automatically acting means for connecting said first mentioned conduit to a supply of air under pressure to force oil through said second mentioned conduit if said last mentioned pressure is above a certain amount.

8. An apparatus for blowing an oil well having in combination, a casing extending to the oil supply, a packer disposed in said casing adjacent the oil supply, a comparatively small conduit in said casing extending through said packer, a source of air under pressure, an oil discharge conduit in said casing extending through said packer to below the surface of the oil supply, means for connecting the space below said packer to the atmosphere to exhaust any pressure therein, means for supplying a volume of air to said space to form a pressure, a supply of air under pressure and means for connecting said supply of air to said first mentioned conduit to force oil through said discharge conduit if said last mentioned pressure is above a certain amount.

9. An apparatus for blowing an oil well having in combination, a casing extending to the oil supply, a packer disposed in said casing adjacent said oil supply, a comparatively small conduit in said casing extending through said packer, a source of air under pressure, an oil discharge conduit in said casing extending through said packer to below the surface of said oil supply, a source of air under pressure adapted to be connected to said first mentioned conduit, a pressure valve shutting off said source of air from said

10 conduit, means for supplying a volume of air to said first mentioned conduit and to said space below said packer to form a pressure therein, a pilot valve operated by said last mentioned pressure if the same is above a certain point and acting to supply air pressure to said pressure valve to open the same and connect said source of air under pressure to said first mentioned conduit for forcing oil through said discharge conduit.

10. The structure set forth in claim 9 and means in said discharge conduit acted upon by said discharged oil for relieving the pressure at said pressure valve and permitting the same to close.

15 11. The structure set forth in claim 9, means adjacent the top of said discharge conduit acted upon by the oil discharged for relieving the pressure on said pressure valve to permit the same to close and for relieving the pressure on said pilot valve to permit the same to move to normal position.

12. An apparatus for blowing an oil well having in combination a casing extending to the oil supply, a packer disposed in said casing adjacent said oil supply, an air supply conduit in said casing extending through said packer, a source of air under pressure, an oil discharge conduit in said casing extending through said packer to below the surface of the oil supply, a driven control valve for connecting said air supply conduit to the atmosphere to exhaust any pressure below said packer, a source of air under pressure, said driven valve acting subsequently to connect said source of air to said air supply conduit to supply air to the chamber below said packer above said oil supply to force a body of oil through said oil discharge conduit.

13. An apparatus for blowing an oil well having in combination, a casing extending to the oil supply, a packer disposed in said casing adjacent said oil supply, an air supply conduit in said casing extending through said packer, a source of air under pressure, an oil discharge conduit in said casing extending through said packer to below the surface of the oil supply, a driven control valve for connecting said air supply conduit to the atmosphere to exhaust any pressure below said packer, a source of air under pressure adapted to be connected to said air supply conduit, a pressure valve shutting off said supply of air under pressure from said air supply conduit, a pilot valve, said driven valve acting to connect said air supply to said pilot valve to connect said chamber below said packer to said pilot valve, said pilot valve acting to connect said source of air under pressure to said pressure valve to open the same and connect said source of air to said air supply conduit if said pressure below said packer is sufficient.

14. An apparatus for blowing an oil well having in combination, a casing extending to the oil supply, means forming a closed chamber in the lower part of said casing adapted to receive oil, the air space of said chamber being varied in accordance with the amount of oil flowing thereto, an air supply conduit extending to said chamber, means for supplying a certain volume of air under pressure to said chamber to create a pressure therein, an oil discharge conduit, and means for utilizing the pressure formed in said chamber for supplying air to said chamber to discharge oil through said oil discharge conduit.

15. An apparatus for blowing an oil well having in combination, a casing extending to the oil supply, means sealing said casing adjacent said

oil supply to form a chamber above the oil supply the air space of which will vary in accordance with the amount of oil flowing thereto, a comparatively small conduit extending to said chamber, a larger discharge conduit extending into said oil supply, means for discharging a certain volume of air through said small conduit to said air space to create a pressure therein varying inversely to the amount of oil in said chamber and means for utilizing said pressure for supplying further air through said small conduit to force oil through said discharge conduit.

16. An apparatus for blowing an oil well having in combination, a casing extending to the oil supply, means forming a chamber at the lower end of said casing above the oil supply the air space of which will vary in accordance with the amount of oil flowing thereto, an air supply conduit extending to said chamber, a discharge conduit extending into said oil supply, means for discharging a certain volume of air through said air supply conduit to said air space to create a pressure therein varying inversely to the amount

of oil in said chamber, a source of air under pressure, means for successively connecting said air supply conduit to the atmosphere and to said source of air under pressure to deliver a certain amount of air into said chamber to create a pressure therein and means for utilizing said pressure if sufficient to supply air under pressure to said air supply conduit for forcing oil through said discharge conduit.

10 17. An apparatus for blowing an oil well having in combination, a casing extending to the oil supply having a closed chamber adjacent the bottom thereof adapted to receive oil from the oil supply, an air supply conduit extending to said chamber, a source of air under pressure, an oil discharge conduit extending to said chamber and below the surface of said oil supply and periodically acting means for successively relieving air pressure from said chamber, supplying a volume of air to said chamber and connecting said chamber to said source of air under pressure.
